Edgar H. Newkirk,

By *George D. Penrose.*

Attorney

UNITED STATES PATENT OFFICE.

EDGAR H. NEWKIRK, OF TULSA, OKLAHOMA.

UNDERREAMER.

1,414,704.

Specification of Letters Patent.

Patented May 2, 1922.

Application filed May 26, 1921. Serial No. 472,635.

To all whom it may concern:

Be it known that I, EDGAR H. NEWKIRK, a citizen of the United States, residing at Tulsa, in the county of Tulsa and State of Oklahoma, have invented certain new and useful Improvements in Underreamers; and I do hereby declare the following to be a full, clear, and exact description of the invention, such as will enable others skilled 10 in the art to which it appertains to make and use the same.

This invention relates to under-reamers, for reaming out or enlarging well holes, and particularly to those devices intended for 15 under-reaming holes drilled in the ground for oil and gas and any other minerals or product, or to prospect for the same.

The object of my invention is to provide a device which can be attached to any standard stem and bit and which will allow the 20 drilling bit to work at the same time as and in advance of the under-reamer to which it is attached.

The present method employed in drilling, 25 is to use a bit attached to the stem, and drill the hole the same size as the bit. Whenever it is desired to enlarge the diameter of the hole, in order to allow deeper casing to enter, it is necessary to withdraw the bit, disconnect it from the stem and then attach an underreamer for enlarging the hole, alternating each operation. This condition applies whenever the hole is cased to a certain point, 30 which occurs in practically all wells.

The under-reamer attached to the bit, according to my invention, will permit drilling 35 and under-reaming at the same time.

With the above and other objects in view, which will appear as the description proceeds, the invention consists in the novel 40 features herein set forth, illustrated in the accompanying drawings and more particularly pointed out in the appended claims.

In the drawings;

Fig. 1 is a cross sectional view of the device showing the under-reamer in cutting position below the casing.

Fig. 2 is a side view of the same.

Fig. 3 is a detail view in cross section, of 50 the under-reamer in closed position, showing the split ring which holds the cutters retracted.

Fig. 4 is a detail view of one of the underreamer lugs, or cutting bits.

Fig. 5 is a view of the latch which holds 55 the lugs in cutting position.

Fig. 6 is a view of one of the release slips, and

Fig. 7 is a view of the working rods.

To put my invention into practice, I provide a reamer body 1, having at its upper end a screw joint 2^a for connecting it to the drill stem 2. At the lower end of the reamer body is a screw joint 15^a for connecting it to a drilling bit 16. The reamer body 65 is provided on its periphery with flat faces 3 and 15 which are adapted to receive a wrench for connecting and disconnecting the string of tools. In the central portion of the reamer body is provided a series of adjoining recesses 18 and 19 in which is secured the mechanism and cutting bits of the under-reamer. In the recess 18 are slidably mounted the release slips 4. Secured in said slips, and projecting therefrom are rods 5 75 which terminate in joints 6, by means of which they are attached to the short rods 7. Through the medium of the joint 8 the rods 7 are swiveled to the single rod 9 which projects from the recess 18 to the recess 19 and 80 is provided with a turnbuckle 9^a, for adjusting the length of the same. Attached to the lower end of the rod 9, by means of the eye 13^a, is a horizontal rod 13 which is secured to and actuates the latches 12 against 85 the springs 14. These latches 12 are provided with beveled portions 12^a and right angular recesses 12^b, which register with the inner edges of the bits or lugs 10.

In the recess 19 are mounted the under-reamer cutting bits or lugs 10, which are swiveled in the main body 1 by the pins 21 in the ear 10^a. Between the cutting lugs 10 and on each side of the rod 9 is a spring 11, which forces the lugs apart and throws them 95 into cutting position.

17 represents the plates which enclose the latches, and 4^a is a split ring which serves to hold the release slips in retracted position.

When it is desired to drill a well deeper and to lower the casing 22 in the hole, my improved under-reamer is applied as follows:

The release slips 4 are pressed inwardly 105 and downwardly due to the angular shape of the recess 18, and the split ring 4^a (Fig. 3) is placed thereover to hold the same in retracted position. This operation, through the medium of the series of working rods 5, 7 and 9, forces the latches 12 down and 110 permits the lugs to retract. It will be noted

that as the rods 7 are forced downwardly, they enter the slots 10^b in the ear 10^a of the lug 10, and through the medium of the pivot 21, spread the ears above the pivot 5 and retract the cutting lugs proper below the pivot.

The string of tools is then placed in position by lowering it through the casing 22. When the split ring 4^a comes in contact 10 with the top of the casing, it is kicked off, and the casing itself serves to hold the lugs retracted until they reach the bottom thereof, whereupon they are automatically released and spread into working position by 15 the spring 11, and becomes locked when the release slips 4 leave the casing, and expand by the working of the springs 14.

In raising the tool to withdraw the same from the hole, the release slips 4 strike the 20 bottom of the casing and contract, due to the rounded edges thereof, causing the latches 12 to release and unlock the lugs 10 so that the lugs upon striking the bottom of the casing, contact and allow the tool 25 to enter the casing.

From the foregoing description, it is believed that my invention can be clearly understood.

It is obvious that numerous changes may 30 be made in the details of construction without departing from the spirit of my invention.

What I claim and desire to secure by Letters Patent is:—

35 1. The combination with a drill stem and bit of an under-reamer, comprising a reamer body provided at both ends with a joint, recesses in said reamer body, a set of lugs swiveled in said recesses and means for locking and unlocking said lugs.

40 2. An under-reamer consisting of a reamer body provided with release slips, a series of working rods attached to said release slips and longitudinally movable in 45 said body, means for adjusting said rods,

a set of cutting lugs swiveled in said body and horizontally expandable and means for expanding said lugs and for locking the same in cutting position.

3. An under-reamer comprising a reamer body, a plurality of recesses therein, release slips slidably mounted in one of said recesses and provided with a series of working rods, a set of cutting lugs swiveled in another of said recesses, and latches actuated by said release slips and working rods, which serve to lock said lugs in cutting position.

4. An under-reamer consisting of a reamer body provided with cutting lugs, release slips mounted in said body in such a manner as to permit their being moved inwardly and downwardly, means for holding said release slips in said position, a series of working rods connected to said release slips and projecting downwardly, terminating in an eye, a horizontal bar engaging said eye and actuating a set of latches, and means for throwing said latches into and out of operative engagement with 70 said lugs.

5. An under-reamer as claimed in claim 2, in which the means for expanding said lugs consists of a plurality of horizontal springs arranged on opposite sides of the 75 working rods and between the cutting lugs.

6. An under-reamer as claimed in claim 2 in which the means for adjusting the working rods consists of a turnbuckle.

7. An under-reamer as claimed in claim 2, in which the cutting lugs are provided with ears, means for pivoting said ears to the reamer body, longitudinally extending recesses in said ears, means for forcing said working rods into engagement with said recesses, forcing the ears apart and retracting the cutting lugs.

In testimony whereof I affix my signature.

EDGAR H. NEWKIRK.
